UNITED STATES PATENT OFFICE.

OSCAR W. BERGGREN, OF WALTHAM, MASSACHUSETTS.

CAN-OPENER.

1,400,406.

Specification of Letters Patent. Patented Dec. 13, 1921.

Application filed August 8, 1919. Serial No. 316,165.

To all whom it may concern:

Be it known that I, OSCAR W. BERGGREN, a citizen of Sweden, residing at Waltham, in the county of Middlesex and State of 5 Massachusetts, have invented certain new and useful Improvements in Can-Openers; and I do hereby declare the following to be a full, clear, and exact description of the invention, such as will enable others skilled 10 in the art to which it appertains to make and use the same.

This invention relates to can openers and the primary object of the invention is to provide an improved can opener which can 15 be effectively used for opening oblong cans and round cans.

A further object of the invention is to provide an improved can opener embodying a pair of oppositely directed cutting blades, 20 one of which is so shaped as to cut cans of oblong shape and the other blade is so shaped as to efficiently cut cans of circular shape.

A further object of the invention is to provide an improved can opener having a pair 25 of oppositely directed blades and an improved can engaging member arranged intermediate the blades so as to form an effective means for positioning the opener on a can.

A still further object of the invention is 30 to provide an improved can opener of the above character, which is durable and efficient in use, one that is simple and easy to manufacture, and one that can be placed upon the market at a reasonable cost.

With these and other objects in view the 35 invention consists in the novel construction, arrangement and formation of parts, as will be hereinafter more specifically described, claimed and illustrated in the accompanying 40 drawings, forming a part thereof, in which:

Figure 1 is a side elevation of the improved can opener.

Fig. 2 is a top plan view of the same.

Fig. 3 is an end elevation of the can 45 opener.

Referring to the drawings in detail, wherein similar reference characters designate corresponding parts throughout the drawings, the numeral 1 generally indicates 50 the improved can opener, which includes the handle 2 formed from a single strip of sheet metal bent intermediate its ends to form spaced side bars 3, which converge toward their forward free ends and receive the can 55 top engaging bar 4, which projects forwardly therefrom. The forward end of the can en-

gaging bar 4 is rounded as at 5 so as to facilitate the movement of the can opener when in operation and this forms a pivotal point for the can opener.

A pair of blades 6 and 7 is arranged on opposite sides of the side bars 3 and projects forwardly therefrom and ends short of the outer end of the bar 4. Each of the blades includes a shank 8 which is arranged in abutting relation to the side bars 3 and the shanks 8 are secured to the outer ends of the side bars 3 by means of rivets 9 which extend entirely through the same and through the bar 4. It will be seen that the rivets 70 not only hold the blades 6 and 7 in position, but also hold the bar 4 against displacement. The blade 6 is formed straight and extends in parallel relation to the bar 4 and is provided with a lower cutting edge 10 and 75 is specially adapted for opening oblong cans. The blade 7 extends outwardly below one edge of the bar 4 in a direction opposite to the blade 6 and is deflected outwardly as at 11, so as to provide substantially a curved 80 blade, so as to facilitate the opening of cans of circular formation. The blade 7 is provided with a cutting edge 12 which is arranged opposite to the cutting edge 10 of the blade 6.

Thus, it will be seen that when one of the blades is in operation the other blade will be positioned on the opposite side of the can and out of its way. When the opposite blade is to be used, the can opener is merely reversed and the blade adjacent to the can is inserted in the top thereof and used in the ordinary manner.

From the foregoing description it can be seen that an improved can opener is provided, which is so constructed that cans of any configuration may be readily opened.

What I claim as new is:

A can opener comprising a bar, a handle having its ends disposed on opposite sides 100 of the bar, knives disposed one against each end of the handle and spaced from the bar thereby, the cutting edge of one of said knives being uppermost and the other lowermost, and securing means for said bar, 105 handle and knives.

In testimony whereof I affix my signature in presence of two witnesses.

OSCAR W. BERGGREN.

Witnesses:

AXEL R. JACOBSON,
ERNEST ANDERSON.
